(57) **CLAIM**

The ornamental design for a sonic/ultrasonic pest repeller, as shown and described.

DESCRIPTION

FIG. 1 is a perspective view of a sonic/ultrasonic pest repeller, showing our new design;

FIG. 2 is a front view of the sonic/ultrasonic pest repeller shown in FIG. 1;

FIG. 3 is a top view of the sonic/ultrasonic pest repeller shown in FIG. 1;

FIG. 4 is a rear view of the sonic/ultrasonic pest repeller shown in FIG. 1;

FIG. 5 is a left side view of the sonic/ultrasonic pest repeller shown in FIG. 1, the right side view being a mirror image thereof; and,

FIG. 6 is a bottom view of the sonic/ultrasonic pest repeller shown in FIG. 1.

The broken line portions of the drawings are for illustrative purposes only, to show the environment of the invention sonic/ultrasonic pest repeller, and form no part of the claim design.
